UNITED STATES PATENT OFFICE.

JOHN F. O'CONNOR, OF CHICAGO, ILLINOIS, ASSIGNOR, BY MESNE ASSIGNMENTS, TO
WILLIAM H. MINER, OF CHICAGO, ILLINOIS.

FRICITION DRAFT-GEAR.

1,086,075.

Specification of Letters Patent.

Patented Feb. 3, 1914.

Application filed December 18, 1909. Serial No. 533,742.

To all whom it may concern:

Be it known that I, JOHN F. O'CONNOR, a citizen of the United States, residing in Chicago, in the county of Cook and State of Illinois, have invented a new and useful Improvement in Friction Draft-Gear, of which the following is a specification.

My invention relates to improvements in friction draft gear for railway cars.

10 My invention consists in the novel construction of parts and devices and in the novel combinations of parts and devices herein shown and described and more particularly specified in the claims.

15 In the accompanying drawing forming a part of this specification, Figure 1 is a side elevation, partly in central, vertical longitudinal section of a friction draft gear or rigging embodying my invention. Fig. 2 is a 20 plan view, partly in horizontal section. Figs. 3, 4, 5 and 6 are vertical cross sections on lines 3—3, 4—4, 5—5 and 6—6, respectively, of Fig. 1. In Fig. 5 however the rear stops are omitted in order to show the laterally 25 projecting follower acting wings of the spring case. Fig. 7 is a detail, partial perspective view, showing one corner of the friction shell and spring case. Fig. 8 is a detail, perspective view of one of the friction shoes. Fig. 9 is a detail elevation of the wedge. Fig. 10 is a detail perspective view, showing a portion of the rear end of the spring case.

30 In the drawing, 1, 1 represents center sills or other draft members of the car frame to which the draft rigging is applied, 2 the front or end sill, 3 the buffer block or plate, 4 the draw-bar, 5 the draft yoke secured to the draw-bar by rivets 6, and interengaging 35 shoulders or gibs 7, 8, 9 the front follower, 10 10^a the stop members having front stops 11, rear stops 12 and an intermediate or limiting stop 13 for the front follower, the stop members being preferably secured to 40 the draft sills by rivets 14.

45 15, 16 and 17 are the springs, nesting one within another.

18 is a longitudinally movable friction shell, having an internal, preferably cylindric, friction face 19, in sliding frictional engagement with the external friction faces 20 of the segmental friction shoes 21, preferably three in number, which fit within the friction shell 18, and which are expanded 50 outward against the friction shell by a cen-

tral wedge 22 acting through the interposed anti-friction rollers 23 which have a rolling action upon the inclined or wedging faces 24 of the wedge 22 and 25 of the friction shoes 21, the rollers being kept in proper 60 position by seats or shoulders 26 on the wedge and 27 on the segmental friction shoes.

28 is a separate piece spring case having a limited, sliding or telescopic movement in 65 respect to the friction shell 18. The spring case 28 has an internal, preferably cylindric, wall 29 conforming in diameter to that of the larger coil spring 15, and it has an external wall 30 which is preferably substantially rectangular in shape to fit between and be guided by the inner upright faces of the stop member 10 and sills 1 and the inner horizontal faces of the draft yoke 5. The friction shell 18 at its rear end 31 fits 70 and telescopes within the front end of the spring case 28 and it is provided with an external limiting flange or shoulder 32 to limit the sliding movement of the friction shell and spring case in respect to each other. 75

The spring case 28 is provided near its rear end on its opposite sides with externally projecting integral wings or members 33, which by engagement with the stops 12 of the stop members, causes the spring case to 80 serve as a rear follower in resisting buffing strains; and the spring case 28 by the engagement of its rear end 34 with the draft yoke 5 causes the spring case to serve as a rear follower under pulling strains. The 85 spring case 28 is preferably furnished with an integral head 35, against which the rear ends of the springs abut, and which is provided with a central recess 36 to receive the nut 37 of the connecting rod 38, the head 39 of which fits in a recess 40 in the wedge 22, the connecting rod extending through the springs and serving to connect all the parts together and hold them in assembled position. The spring seat or cap 41 is interposed between the springs at the front ends thereof and the friction shoes 21, the same having a central recess or cut away portion 42 to give the cap 41 an outer bearing face 43 only against the adjacent ends of the friction shoes 21.

The integral follower-acting wings or projections 33 on the spring case are located intermediate the ends thereof, that is to say, at a distance removed from the rear end of 110

the spring case so that the front and rear stops 11, 12 may be at the standard or regular distance apart, and enable the draft rigging at the same time to have springs 15, 16, 5 17, which are materially longer and have a materially greater compressive movement or travel than regular or standard springs. My improved friction draft rigging is thus adapted to interchangeably go into any car 10 having stops arranged at standard distance apart, and at the same time afford a materially greater cushioning movement and cushioning capacity. The draft gear is removably supported on the draft sills or 15 frame members 1, 1 of the car, preferably by a tie-plate 44 having short connecting bolts 45.

The friction shell 18 and spring case 28 are preferably telescopically or slidingly 20 connected together by connecting bolts 46 at the four corners of the spring case 28, and which extend through connecting members 47 on the spring case and 48 on the friction shell, the spring case having corner recesses 25 49 to accommodate the heads of the connecting bolts.

The front stop member 10 is preferably 30 of malleable iron and has the front stop 11 and limiting stop 13 formed integrally together. The front stop member 10 is also provided with an upper horizontal guide flange 50 for the follower, and with inwardly projecting horizontal and longitudinally extending strengthening flanges 51 35 and an upright, transversely extending terminal flange 52. At its front end, the stop member 10 is also provided with upper and lower strengthening flanges or webs 53. The rear stop members 10^a are preferably in separate pieces from the front stop members 10. By making the stop members which have or 40 bear the front stop or stops in separate pieces from the stop members having or bearing the rear stop or stops, the malleable iron or 45 cast metal stop members are materially reduced in length or size and adapted to be cast or made more readily, cheaply and perfectly.

I claim:—
50 1. In a friction draft rigging, the combination with stop members having front and

rear stops at standard distances apart, of a friction shell, a spring case, a spring within said case of greater than standard length and compressive movement, said spring case 55 having external projections forward of its rear end for engagement with the rear stops, said spring case being in a separate piece from said friction shell and having a limited sliding movement in respect thereto, and 60 connecting bolts between said friction shell and spring case and slidably in respect thereto, substantially as specified.

2. In a friction draft rigging, the combination with stop members having front and 65 rear stops at standard distances apart, of a friction shell, a spring case, a spring within said case of greater than standard length and compressive movement, said spring case having external projections forward of its 70 rear end for engagement with the rear stops, said spring case being in a separate piece from said friction shell and having a limited sliding movement in respect thereto, and connecting bolts between said friction shell 75 and spring case, said spring case being internally cylindric and externally rectangular, and said connecting bolts being at the corners of said spring case, substantially as 80 specified.

3. In a friction draft rigging, the combination with stop members having front and rear stops, of a friction shell, a spring case, said case and shell being telescoped to thereby maintain the same in alinement, and said 85 spring case having external projections forward of its rear end for engagement with said rear stops, a wedge and friction shoes within said shell, a spring within said case of greater than standard length and compressive movement, and means connecting said shell and case adapted to prevent the same from being separated and at the same time permitting relative movement therebetween, said means including an element connected to one of said members and loosely 90 engaging the other, substantially as specified.

JOHN F. O'CONNOR.
